(57) **CLAIM**

The ornamental design for an eyeglasses visor and case, as shown and described.

DESCRIPTION

FIG. 1 is a front elevational view of the eyeglasses visor and case with unclaimed neck string embodying the new design;

FIG. 2 is a top elevational view thereof;

FIG. 3 is a bottom plan view of the eyeglasses visor and case;

FIGS. 4–6 are side, front, and back views thereof;

FIG. 7 is a bottom view of the eyeglasses visor and case;

FIG. 8 is a bottom view thereof with the top-positioned protective flap in a released position;

FIG. 9 is a front perspective view thereof depicting unclaimed eyeglasses positioned within the eyeglasses visor and case;

FIG. 10 is a rear perspective view thereof depicting unclaimed eyeglasses positioned within the eyeglasses visor; and,

FIG. 11 is a bottom view thereof depicting unclaimed eyeglasses in a closed position in the eyeglasses case.

The broken line showing of eyeglasses and neck straps is for illustrative purposes only and forms no part of the claimed design.
